ARTHUR E. WALSH, OF EVANSTON, ILLINOIS

HAIR WAVER AND METHOD

Application filed May 9, 1927. Serial No. 189,917.

This invention relates to an improved hair waver and method and generally its objects are to provide a wave and particularly a Marcel wave of greater life and durability and of improved form and appearance and a generally improved and simplified device that may be economically produced and conveniently manipulated to form the same.

The invention is illustrated in the accompanying drawings in which:

Fig. 1 is a top plan view of a device embodying the present invention;

Fig. 2 is a longitudinal section taken on the line 2—2 of Fig. 1;

Fig. 3 is a view similar to Fig. 2 with the device in closed position;

Fig. 4 is a longitudinal section taken on the line 4—4 of Fig. 2;

Figs. 5, 6, 7 and 8 are diagrammatic views showing four steps in the operation of the device;

Fig. 9 is a transverse section taken on the line 9—9 of Fig. 2;

Fig. 10 is a transverse section taken on the line 10—10 of Fig. 2;

Fig. 11 is a transverse section taken on the line 11—11 of Fig. 2;

Fig. 12 is a section taken on the line 12—12 of Fig. 2;

Fig. 13 is a side elevational view of the device in open position;

Fig. 14 is a detail section taken on the line 14—14 of Fig. 2;

Fig. 15 is a longitudinal section taken on the line 15—15 of Fig. 2;

Figs. 16 and 17 show, more or less diagrammatically, waves produced in accordance with the present invention; and

Fig. 18 is a fragmentary section view showing another form of handle and hair shifter mounting embodying the present invention.

Referring to the drawings the device shown comprises a longitudinal prong 10, a pivoted waving member 12 swingable into and out of cooperation with the prong 10, a pair of pivoted or hinged waving jaws 14, swingable into and out of cooperation with the waving member 12; and a comb or hair gripping, shifting and measuring mechanism designated generally at 15. The waving

member 12 is of generally cylindrical tubular formation closed at one end at 16 and telescopically mounted at its opposite end upon a member 17 pivoted at 18 upon the inner end of the prong member 10. The waving member 12 is preferably provided internally with a suitable heating element, shown more or less diagrammatically at 20. The heater 20 may be of any suitable or preferred form, such as for example a resistance coil with suitable circuit connections, as well understood in the art.

The prong 10 constitutes, in effect, the back-bone of the device and its upper surface is of concave curvature at 22, (Fig. 11) conforming with the cylindrical exterior of the waving member 12. The member 17 may be in the form of a casting with the cylindrical member 12 attached to swing with the same about the pivot 18. The prong or base member 10 may likewise be in the form of a casting, although this may be varied, and the inner end of the member 10 is provided with a handle 25.

The handle 25 may be of a hard rubber 75 composition, or any other suitable or preferred material and it is of generally channel shaped transverse section forming an internal longitudinal trough 26, in which is mounted a frame 28. The frame 28 is of 80 channel formation conforming with the shape of the trough 26 and it may be held in place in the handle 25 as by means of suitable pins or rivets 29. The inner end of the prong 10 has a tongue 30, which extends into the trough 26 and is riveted at 32 to the base of the frame 28. The prong member 10 may be recessed adjacent the knuckle at the pivot 18 to permit the waving member 12 to swing into parallel relation with the upper surface 90 22 of the prong 10 in closing.

Connected with the handle 25 by two pairs of folding links 34 for movement toward and from the handle 25 in parallel relation thereto is a second handle 35. This second handle 35 may, like the handle 25, be of a hard rubber composition, or any other suitable or preferred material and it, too, is of generally channel shaped formation with an internal longitudinal trough 36. A generally chan-

nel shaped frame 38 is mounted in the handle 35. It conforms substantially with the trough 36 and may be held in place by suitable pins or rivets 39.

5 There are two pairs of links 34, one pair adjacent each of the opposite sides of the device, as shown in Fig. 9. The two links 34 of each pair are pivoted together at 40 where they cross between their ends and the rear ends of the two links of each pair are fixedly pivoted at 42 and 43 to the upper and lower frame members 38 and 28, respectively. The crossing of the links 34 spaces the upper ends, for example, from 10 the adjacent sides of the frame 38, and suitable spacers or washers 45 may, therefore, be interposed between the upper rear ends of the links 34 and the adjacent sides of the frame 38.

15 20 The forward or opposite ends of the links 34 have sliding pivotal connection with the sides of the frame members 28 and 38 through pins 46 and longitudinally elongated slots 48 in the sides of the frame members 28 and 38.

25 The comb or hair gripping, shifting and measuring mechanism 15 comprises a rod of generally circular section having its outer end 50 disposed parallel with and along the 30 outer side of one or the other of the waving jaws or leaves 14 and preferably hugging the leaf or jaw 14 and below the free edge thereof to draw the strands or lock of hair over the same, as will hereinafter appear. 35 A wire 52 wrapped helically upon the rod portion 50 and secured thereto, gives the rod portion 50 a comb-like effect on the hair. The rod is turned laterally at 54 and rearwardly at 55 with the rearwardly extending 40 portion 55 substantially parallel with the rod portion 50 and entering the trough defined by the frame 38 in the upper handle 35.

45 Pivoted at 56 to the rod and swingable into and out of cooperation with the rod portion 50 is a gripping prong 57. The prong 57 comprises a length of wire 58 provided with a covering 59, which may be in the form of a tube of rubber or the like. The outer end of the wire prong is releasably 50 secured by means of a suitable catch 59' to the adjacent end of the rod portion 50. By springing the catch 59' slightly the outer end of the prong 57 may be released and the prong 57 swung into the position shown 55 in dotted lines at 60 in Fig. 2, for example, whereupon the strands or lock of hair may be arranged between the prong 57 and rod portion 50. Then by closing the prong 57 upon the hair and into cooperation with the rod portion 50 the catch 59 is engaged and the hair is gripped between the rod portion 50 and prong 57. The gripping of the hair is sufficient to hold the same adequately to 60 shift and measure the hair, but is sufficient 65 ly yieldable to permit slipping the gripping

elements 57 and 50 along the strands or lock of hair in the direction of their length without discomfort or undue stress thereon.

65 The rod portion 50 and cooperating prong 57 are yieldingly held against the outer side of the iron or waving jaw 14 by a leaf spring 62 secured at 63 in the handle 35. Keyed at 64 (Fig. 14) upon the rod portion 55 is a disc 65 having its periphery flattened at 66 and the spring 62 pressing against the end 70 of the flattened portion 66 yieldingly swings the outer end of the rod into cooperation with the leaf or jaw 14. By closing the waving member 12 sufficiently to permit the rod portion 50 to clear the same, the outer end of the rod may be swung over into cooperation with the other leaf or jaw 14, whereupon, the cooperation of the spring 62 with the opposite end of the flat portion 66 will yieldingly hold the outer end of the rod against 75 the other jaw.

80 The rod portion 55 passes through and bears in lugs 68 and 69 struck down from the top of the frame 38.

85 The waving member 12 is closed into cooperation with the complementary curved surface 22 of the member 10 with the initial movement of the handle 35 toward the handle 25 through a link 70 pivoted at 72 to the end piece 17 of the waving member 12. The 90 upper or opposite end of the link 70 is pivoted at 73 in a carriage 74 having outturned arms 75 mounted for longitudinal sliding movement in the handle 35 upon lugs 76 which may be struck in from the sides of the 95 frame 38, as shown in Fig. 10. A rod 77 (Figs. 2 and 9) is fixedly anchored at its rear end in a lug 78 struck in laterally from one side of the frame 38 and the opposite end of the rod 77 passes freely through an aperture in a lug 79 (Figs. 2 and 10) struck laterally from one of the arms 75 of the carriage 100 74. A spring 80 is coiled about the rod 77 and interposed between the lugs 78 and 79, and with the initial movement of the handle 105 35 toward the handle 25, the waving member 12 is swung quickly into cooperation with the prong 10 through the toggle action provided by the link 70 and the pivoting of the waving member at 18. As the movement 110 of the handle 35 toward the handle 25 continues after cooperation of the waving member 12 with the prong 10, the upper end of the link 70, with its carriage 74, is forced rearwardly against the tension of the spring 115 80 which permits the closing of the handles to continue without interference by the link 70 and the compression of the spring with the continued closing of the handles further tensions the waving member 12 upon the 120 member 10.

125 For shifting the comb alternately in opposite directions with the successive closing movements of the handle 35 toward the handle 25, a bracket 85 is fixed upon the rod por- 130

tion 55 against movement longitudinally with respect to the rod portion 55. The upper end of the bracket 85 may, for example, be rolled at 86 about the reduced portion 87 of the rod portion 55 and held between the shoulders at the ends of the reduced portion 87 against longitudinal movement relative to the rod. A shifting link 88 is pivoted at 89 to the depending portion of the bracket 85 and this link 88 is normally held in and returned to vertical position by a spring 90 coiled at 91 upon an extension of the pin pivoting the link to the bracket 85 and with its opposite ends turned into engagement with the opposite edges of the link 88.

Struck up from the bottom of the frame 28 into vertical position along one side of the lower end of the link 88 is a flange 93 having stop shoulders 94 and 95 at its opposite ends and a centrally raised cam surface 96 therebetween. With the parts in the relative positions shown in Fig. 2, closing of the handle 35 toward the handle 25 swings the pin 98 at the lower end of the link 88 into engagement with the shoulder 94, and as the closing movement continues after the pin 98 engages the shoulder 94, the upper end of the link 88 swings in a clockwise direction about the axis of the pin 98 and shifts the comb or rod 50 rearwardly through the bracket 85. The carriage 85 and the pivoted upper end of the link 88 being positioned on the opposite side of the centrally raised cam portion 96, by the closing movement with the parts as shown in Fig. 3, the following opening or separation of the handles frees the lower end of the link 88, and it is swung into vertical position upon the opposite side of the centrally raised cam surface 96 so that with the succeeding closing movement of the handles the pin 98 will be first swung into engagement with the shoulder 95, whereupon the upper end of the link 88 will, with the continued closing movement of the handles, be swung in a counterclockwise direction, shifting the comb and rod 50 forwardly or outwardly. Then, with the next separation or opening of the handles, the link 88 will be returned to the position shown in Fig. 2.

For the purpose of swinging the waving jaws or irons 14 into and out of cooperation with the waving member 12 by the closing and opening of the handles 25 and 35, a pair of shoes 100 (Figs. 2 and 12) are pivoted at 102 to the sides of the member 10 between the pivot 18 and the tongue 30. The outer edges of the shoes 100 are flanged at 103 above the pivot 102 and this flange is continued at 104 below the pivot 102. The shoes 100 are swung in a counterclockwise direction with each closing movement of the handle 35 toward the handle 25 through links 105 pivoted at 106 to the shoes 100, and at 46 to the links 34. The normal open positions of the waving jaws or irons 14 are shown

in Figures 11 and 12, and the forward sliding movement of the lower forward ends of the links 34, which accompanies movement of the handle 35 toward the handle 25, swings the shoes 100 in a counterclockwise direction about the pivot 102 through the links 105, engaging the flanged upper ends 103 of the shoes 100 with the tapered or chamfered rear surfaces 108 of the jaws or irons 14 and closing the jaws or irons 14 into cooperation with the external surface of the waving member 12, which is, in the operation of the device, previously engaged with the prong 10. The links 105 are shown as integrally connected by a cross piece 110 in Fig. 2, and in Fig. 12 the rear ends of the jaws 14 have further tapered or chamfered surfaces 112 which the iron closing shoes engage in closing and holding the jaws 14 in cooperation with the waving member 12.

The jaws or irons 14 also have at their rear ends lugs depending below the pivot 18 and tapered or chamfered at 114 (Figs. 2 and 12). In the separation or opening movement of the handles, the shoes 100 are swung in a clockwise direction and the flanges 104 at the lower ends thereof engage the depending chamfered surfaces 114 and spread or swing the upper jaw or leaf portions of the irons 14 into open position.

The jaws or waving members 14 are pivoted or hinged each on a longitudinal pin 120 journaled in opposite sides of the prong or back-bone member 10 as shown in Figs. 11 and 13. For journaling the pins 120, the member 10 has lateral lugs 121, and the inner surfaces of the members 14 are concave and arcuate in form at 122 (Fig. 11). The surfaces 122 are supplemental, one to the other, and when the jaws 14 are closed upon the waving member 12, each forms a continuation of the other and with the surface 22, which forms a continuation of the surfaces 122, they conform to the circular periphery of the waving member 12. It should be noted that the members 14 embrace the greater portion of the waving member 12 when closed thereupon, leaving, as shown in Fig. 11, a slight gap 125 between their free ends through and from which the strands of hair may extend between the members 14 and the member 12.

By providing hinged or pivoted waving members 14, which are adapted to be closed upon the waving member 12, it will be apparent that a wave greater than a half circle may be imparted to the strands or lock of hair. This is an important aspect of the invention, in that I find that thereby the depth of the wave may be materially increased and that by waving past center or past the half circle, the top of the wave is directed inwardly on each side. I find that this fixes the wave better and materially increases the life and durability thereof.

Where the channel or trough shape member is in one piece, it cannot be greater than a half circle, or semicircular, without interfering with the swinging of the complementary waving member into and out of cooperation therewith.

Where the trough-shaped waving member is not greater than a semicircle, the wave produced thereby will, likewise, not be greater than a semicircle, and the top of the wave at each side will terminate with the spreading of the wave and without any in-turning thereof. I find that such a wave is not durable and is of a very short life, particularly under damp, warm climate conditions.

With the present invention, however, the swinging of the jaws or waving members 14 permits forming the wave of much greater than semicircular form without in any way interfering with the positioning of the waving member 12 between the members 14 or with its movement into and out of cooperation with the member 10.

The handles 25 and 35 are formed, dimensioned and positioned to be conveniently grasped in the hand of a woman, and the entire operation is effected by alternately pressing the handles together and releasing them. The links 34 connect the handles 25 and 35 and the sliding movement of the forward ends of the links which terminate in the handle 25 imparts the closing and opening movements to the waving members 14. The closing action of the waving members 14 as imparted by these links, is such that a final tensioning and firm gripping of the members 14 about the member 12 is secured.

For the purpose of separating the handles merely by releasing them after they are pressed together, a pair of coiled springs 128 are connected between the two links of each pair, as shown in Figs. 2 and 9, these springs 128 being connected to swing the links 34 in a direction to separate the handles 25 and 35 upon their release.

In use, assuming that the device is in the open position as shown in Fig. 2, the strands or lock of hair, as designated at 135 in Fig. 11, are laid over the upper free edges of the open waving members 14 and between these waving members and the waving member 12, shown fragmentarily in its open position in Fig. 11, and on through and between the rod portion 50 and the rubber covered prong 57, which is closed upon the hair and latched by the catch 59' to grip the hair between the rod 50 and the prong 57. The wrapping of the wire 52 about the rod 50 forms, in effect, a comb which holds the strands of hair against slipping or displacement between the prongs 50 and 57 in the direction of the lengths of these prongs.

The device of the present invention is adapted for working in either direction,

simply by reversing the position of the prongs 50 and 57 from one jaw 14 to the other.

With the strands of hair 135 arranged over the waving members 14 and between them and the waving member 12 and gripped between the comb 50 and the cooperating prong 57, the initial closing of the handles swings the waving member 12 downwardly, through the link 70 into cooperation with the upper surface 22 of the prong or back-bone member 10. This closing of the waving member 12 into cooperation with the member 10 is positive and rapid, the waving member 12 being swung into cooperation with the member 10 with very little movement of the handle 35 toward the handle 25. As the member 12 comes into cooperation with the member 10, the strands of hair are firmly and securely gripped therebetween, and the following movement of the upper end of the link 70 against the tension of the spring 80 tensions and imparts an additional grip to the hair between these members.

Simultaneously with this closing of the waving member 12 into cooperation with the waving member 10, the waving member 50 with its cooperating prong 57 move downwardly (Fig. 2), drawing the strands of hair over the upper edge of the adjacent waving member 14 and slipping over the hair transversely with respect to the comb.

At the same time, the lower end of the link 88 is swung in a clockwise direction against the tension of the spring 90 until the pin 98 engages or abuts the shoulder 94, whereupon the upper end of the link 88 swings rearwardly in a clockwise direction, shifting the comb 50 with its cooperating prong 57 rearwardly from the position shown at A in Fig. 5 to the position B in Fig. 6, the comb continuing to slip over the strands of hair between it transversely with respect to the length of the comb.

The forward sliding movement of the forward ends of the links 34 adjacent the lower handle 25, swing the shoes 100 in a counter-clockwise direction with the closing of the handles and toward the limit of the longitudinal shifting movement of the comb, the engagement of the flanges 103 with the chamfered surfaces 108 and 112 closes the jaws or waving members 14 into cooperation with the waving member 12 and tightly about the strands of hair therebetween, imparting a wave of greater than semicircular formation with the top of the wave at each side directed inwardly and firmly and durably fixed. The final position of the comb is shown at B in Figs. 6 and 11.

The shifting of the comb 15 lays the strands of hair at an angle or obliquely between the adjacent jaw 14 and the waving member 12, and this increases the length of the lock of hair which is waved or ironed between the members 12 and 14. Further-

more, this shifting tends to lay the waves produced by the members 12 and 14 over laterally with the result that a wave which is flat and of excellent appearance is produced.

5 The comb 15, with its cooperating prong 57, at the same time measures the amount of hair which is to be fed between the waving members upon the following opening movement thereof.

10 Upon completing this closing of the device, the handles are released and they are thereupon separated by the springs 128. The lower end of the link 88 is thereupon swung past the intermediate raised cam portion 96 by the spring 90 until this link 88 is positioned substantially vertically on the opposite side of the intermediate raised cam portion 96, the jaws 14 are forced positively 20 to open position by the accompanying clockwise swinging of the shoes 100, the waving member 12 is swung to open position through the link 70, and the comb 50 and cooperating prong 57 are swung up into position adjacent the side of the adjacent waving member 14, as shown in Fig. 7, by the spring 62.

25 The handles 25 and 35 are thereupon again closed and the waving operation is repeated, with the exception that the comb element is shifted forwardly into the position shown at D in Fig. 8. This shifts or directs the strands of hair 135 in the reverse direction from where they are gripped or held between the waving members 10 and 12, and produces the wave across the wave produced between the members 12 and 14. The forward shifting of the comb is accomplished by swinging the lower end of the link 88 in a counterclockwise direction with the initial closing of the handles until the pin 98 engages the shoulder 95, whereupon, the upper end of the link 88 is swun in a counterclockwise direction and shifts the comb forwardly. This shifting again lays the strands of hair at an angle or obliquely between the members 12 and 14 only in the reverse direction, again increasing the waving cooperation therewith and laying the wave produced between the members 12 and 14 over flat.

30 The following opening movement positions the parts again as shown in Fig. 2, and the operations may be continued as desired, the shifting of the comb alternately in opposite directions imparting the wave across the waves produced between the members 12 and 14, and this shifting with the accompanying lowering and raising of the comb successively measuring and feeding equal lengths or increments of hair to position between the 35 waving members 10 and 12 with each opening of the device. The manner of increasing the circular formation of the wave past center, as well as the manner of forming the waves across the waves produced between the members 12 and 14 and laying the waves

produced between the members 12 and 14 over flat, are important aspects of the present invention. The manner of shifting the strands of hair alternately in opposite directions from where they are gripped between the members 10 and 12 and the manner of successively measuring and feeding uniform lengths of hair to position between the waving members 10 and 12 with each separation of the handles 25 and 35, are also important aspects of the invention.

40 The Marcel effect produced is shown more or less diagrammatically in Figs. 16 and 17. The waves 140 produced by the waving members 12 and 14 are relatively deep, distinct and durable. They may be greater than semicircular in each direction, as indicated more or less diagrammatically at 142, the resulting turning in past center in each direction at 142 holding and better fixing and defining the waves 140. The shifting of the comb mechanism alternately in opposite directions imparts the waves across the waves 140 and lays the waves 140 over alternately in opposite directions, producing an effect which is flat and in which the waves are at the same time relatively deep and well fixed. The waves 140 may, for example, be greater than semicircular alternately in each direction and, at the same time, a relatively flat effect is secured, as indicated more or less diagrammatically in Fig. 17, due to the laying of the waves 140 over in opposite directions by the lateral shifting and accompanying ironing action.

45 It will be understood that the heating means 20 for the waving member 12 may be provided with suitable conductors 150 which may be led in through the handle 25 and end piece 17 into the cylindrical waving member 12 and suitably connected to the resistance coil 20. The opposite ends of the conductors may be provided with a suitable connector adapted for connection, for example, with the desired electricity outlet.

50 In the embodiment of Fig. 18 the rear bearing for the rod portion 55' is positioned up adjacent the bracket 85' and the rearward shifting of the rod is permitted without projecting the same from the rear end of the adjacent handle. In this case, the upper end of the link 70' and the upper end of the link 88' are provided with similar sliding mountings in the upper handle. These mountings may, in fact, be interchangeable, or their structure is at least standardized. The coiled spring 80' is interposed between the bearing 69' and an apertured lug 152 carried by the carriage 74'. Instead of the inturned lugs of the previous embodiment, the carriages 74' and 85' have lateral lugs 156 which have sliding mounting in longitudinal slots 158 in the sides of the upper handle frame.

55 I do not, of course, intend to be limited to 130

the details of the particular embodiments of the invention selected for illustration.

I contemplate making the comb removable so that it may be gripped upon the hair and then be conveniently attached to the device and I also contemplate the provision of means for adjusting the rod portion 54 for adjusting the amount of hair fed between the waving members with each feeding operation.

I claim:

1. In a hair waver, the combination of a pair of outer waving members each having a concave inner surface of the same curvature from end to end longitudinally of said outer waving members, an inner waving member pivotally connected with said outer waving members to swing into and out of cooperation with said outer waving members and of equal cross section from end to end, said outer waving members being pivoted to swing laterally into and out of cooperation with said inner waving member and substantially enclosing said inner waving member when closed into cooperation therewith, the concave inner surfaces of said outer waving members substantially following the periphery of said inner waving member and having uniform cooperation with said inner waving member longitudinally of said inner and outer waving members when closed into cooperation therewith and common handle means for swinging the inner waving member into cooperation with the outer waving members and for closing the outer waving members laterally upon said inner waving member.
2. In a hair waver, the combination of a tubular inner waving member of equal cross section from end to end, a pair of clamping members movable laterally into and out of cooperation with said inner waving member and substantially enclosing said inner waving member when in cooperation therewith, each said clamping members having a concave inner surface of the same curvature from end to end longitudinally of said clamping members, the concave inner surfaces of said clamping members substantially following the outer surface of said inner waving member and having uniform cooperation with said inner waving member longitudinally of said member when closed into cooperation therewith, a permanent operative connection between said inner waving member and said clamping members connecting said members when in cooperation and when out of cooperation, and means for bringing said inner waving member and said clamping members into and out of cooperation through said operative connection.
3. In a hair waver, the combination of a tubular inner waving member of equal cross section from end to end, a pair of clamping members movable laterally into and out of cooperation with said inner waving member and substantially enclosing said inner waving member when in cooperation therewith, each said clamping members having a concave inner surface of the same curvature from end to end longitudinally of said clamping members, the concave inner surfaces of said clamping members substantially following the outer surface of said inner waving member and having uniform cooperation with said inner waving member longitudinally of said member when closed into cooperation therewith, a permanent operative connection between said inner waving member and said clamping members connecting said members when in cooperation and when out of cooperation, and means for bringing said inner waving member and said clamping members into and out of cooperation through said operative connection.

ing member when in cooperation therewith, each said clamping members having a concave inner surface of the same curvature from end to end longitudinally of said clamping members, the concave inner surfaces of said clamping members substantially following the outer surface of said inner waving member and having uniform cooperation with said inner waving member longitudinally of said member when closed into cooperation therewith.

4. In a hair waver, means for gripping a lock of hair, means for drawing the hair obliquely from said gripping means, and means for forming a wave across the obliquely drawn hair portion.

5. In a device of the class described, the combination of a cylindrical waving member, a pair of swingably mounted waving members adapted to be opened to receive said first member and adapted to be closed into cooperation therewith with their free margins extending past center and separated to permit the strands of hair to extend into and from between the waving members, the inner surfaces of said last waving members conforming with the periphery of said first waving member, and when closed into cooperation therewith each forming a continuation of the other and means cooperable with said cylindrical waving member for gripping the hair thereto independently of said swingably mounted waving members.

6. In a device of the class described, the combination of a prong, a cylindrical waving member swingable into cooperation therewith to grip the hair therebetween, and a pair of waving members hinged to said prong and adapted to be closed into cooperation with said cylindrical waving member.

7. In a hair waver, a pair of waver members adapted for gripping a lock of hair between them, means for opening and closing said waver members, and means for feeding the lock of hair progressively between said members.

8. In a hair waver, a prong, a waving member swingable into cooperation therewith to grip the hair therebetween, waving means cooperable with said last waving member, and means for shifting the hair alternately in opposite directions and for feeding uniform lengths of hair successively between said prong and said waving member.

9. In combination, a prong, a waving member swingable into and out of cooperation therewith and a pair of waving members pivoted to said prong and swingable laterally into and out of cooperation with said first waving member.

10. In combination, a prong, a waving member swingable into and out of cooperation therewith, a pair of waving members pivoted to said prong and swingable laterally into and out of cooperation with said first waving member.

member, and comb means for gripping a lock of hair and shiftable longitudinally in opposite directions and laterally from and toward said waving members.

5 11. In combination, a prong, a waving member swingable into and out of cooperation therewith, a pair of waving members pivoted to said prong and swingable laterally into and out of cooperation with said first waving member, comb means for gripping a lock of hair and shiftable longitudinally in opposite directions and laterally from and toward said waving members, and common means for swinging said first waving member 10 into cooperation with said prong, said second waving members into cooperation with said first waving member and for operating said comb means.

15 12. In combination, a pair of handles adapted to be opened and closed, a prong on one handle, a waving member pivoted to said prong, a connection between the other handle and said waving member for swinging said member into cooperation with said prong at 20 relatively great speed with the initial closing of said handles, and means for yieldingly tensioning the cooperation of said waving member with said prong with the continued closing of said handles.

25 13. In combination, a pair of handles adapted to be opened and closed, a prong on one handle, a waving member pivoted to said prong, and a toggle connection between the other handles and said waving member for 30 swinging said member into cooperation with said prong upon closing said handles.

35 14. In combination, a pair of handles adapted to be opened and closed, a prong on one handle, a waving member pivoted to said 40 prong, a connection between the other handle and said waving member for swinging said member into cooperation with said prong upon closing said handles, a pair of waving members pivoted to said prong and swingable laterally into cooperation with said first waving member, folding link means connecting the handles and having sliding pivotal connection therewith, and means operated by the 45 sliding movement of said link means for closing said last waving members into cooperation with said first waving member.

50 15. In combination, a pair of handles adapted to be opened and closed, a prong on one handle, a waving member pivoted to 55 said prong, a connection between the other handle and said waving member for swinging said member into cooperation with said prong upon closing said handles, a pair of waving members pivoted to said prong and 60 swingable laterally into cooperation with said first waving member, folding link means connecting the handles and having sliding pivotal connection therewith, means operated by the sliding movement of said link 65 means for closing said last waving members

into cooperation with said first waving member, said means comprising cam means on said last waving members, and shoe means swingable into cooperation therewith.

70 16. In combination, a pair of handles adapted to be opened and closed, comb means mounted on one of said handles for longitudinal and lateral movement relative thereto, a shifting member swingable on said comb means by closing of the handles, stop means cooperable with said shifting member for causing said member to shift said comb means with the closing of said handles and means for moving said comb means laterally.

75 17. In combination, a pair of handles adapted to be opened and closed, comb means mounted on one of said handles for longitudinal and lateral movement relative thereto, shifting means swingable on said comb means by closing of the handles, said shifting means comprising a shifting member pivoted at one end on the comb means and swingable at its opposite end between a pair of stops and alternately into engagement with said stops to shift the comb means alternately in opposite directions with the closing of said handles and means for moving said comb means laterally.

80 18. In combination, a pair of handles adapted to be opened and closed, a prong on one handle, a waving member pivoted to said prong, a connection between the other handle and said waving member for swinging said member into cooperation with said prong upon closing said handles, a pair of waving members pivoted to said prong and swingable laterally into cooperation with said first waving members, folding link means connecting the handles and having sliding pivotal connection therewith, means operated by the sliding movement of said link means for closing said last waving members into cooperation with said first waving members with the closing of said handles.

85 100 105 110 115

In witness whereof, I hereunto subscribe my name this 7th day of May, 1927.

ARTHUR E. WALSH.
